UNITED STATES PATENT OFFICE.

JOHN W. ANDERSON, OF LANCASTER, PENNSYLVANIA.

WASH-BOILER TANK.

SPECIFICATION forming part of Letters Patent No. 400,425, dated April 2, 1889.

Application filed June 10, 1886. Renewed November 28, 1887. Serial No. 256,365. (No model.)

To all whom it may concern:

Be it known that I, JOHN W. ANDERSON, a citizen of the United States, residing at Lancaster, in the county of Lancaster and State 5 of Pennsylvania, have invented certain new and useful Improvements in Wash-Boiler Tanks, of which the following is a specification.

My invention is a portable stand 10 mounted with a boiler-tank, which serves as a convenient vessel for washing clothes therein by the aid of the ordinary wash-board or means for operating on them, and in which vessel the wash-water is heated and kept hot 15 by an oil-stove or other heater arranged thereunder.

It consists more particularly of improvements in the construction of the tank's bottom, and to a jacket attached thereto beneath 20 it, which communicates interiorly with the tank and forms flues between it and said bottom extending from a fire-confine lower down, into which the heat of the stove is directed, as hereinafter more fully described, and pointed 25 out by the claims.

In the drawings, Figure 1 is a longitudinal vertical section of my tank and stand with an oil-stove mounted thereon. Fig. 2 is a vertical cross-section of the tank; and Fig. 3 is a 30 bottom view of the jacket, the lower marginal sheet being removed to disclose the waterways therein.

In the further description the same letters denote the same parts in all the views.

Though my device is illustrated as mounted 35 on a stand, as a suds-tank, the essential features of my improvement are applicable also to ordinary wash-boilers, and other vessels adapted to sit directly in openings in tops of 40 cooking stoves and ranges, said features relating, mainly, to the construction of the fire box or confine and to the passages in the dependent jacket attached to the bottom of said water-heating vessel. Said vessel is denoted 45 by letter A and the water-level therein by X, its supports by a, which latter are battened together by the cross-pieces a'. The hipped bottom E E' of said vessel has the longitudinally dished or slant sections E', which latter are 50 secured to the upper edges of the ends A' A'',

and the sections E and E' are also extended up laterally and secured on top of the sides A³. The parts A' A² A³ compose a wooden frame, to which said metal parts are nailed at b and d in position, as shown. To the under side 55 of said hipped bottom are riveted or soldered the flanged side pieces, V V', made to conform to the under side of said bottom and extended nearly from end to end thereof. Said side pieces are parallel to each other and are 60 joined together by the transverse fire plates or sheets D. Said side pieces and fire-plates are made, preferably, of malleable iron in sectional castings. Said fire-plates are arranged parallel to said bottom, and a little distance 65 below it, excepting at their outer ends, which are bent up and joined to the sections E' of said bottom, as shown. The inner ends of said plates D are turned downward, and they, in connection with the side fire-plates, D', 70 compose the pendent fire confine or box D², which serves to inclose and direct upward all the heat from an oil-stove, J, or other heater, arranged below and part way inserted into 75 said confine.

The side pieces, V V', are provided with the studs or lugs S in the walls at the corners of said fire-box D², and the plates D D' abut against said studs S, as shown in Fig. 3, thus causing the water-passages P P' B to be 80 formed between the plates D' and the side pieces, V V', and between the plates D and the sheet-metal sections Z Z', respectively. The side pieces, V V', are provided at their lower edges with interior shoulders, on which 85 are secured the lateral edges of said sheet-metal sections Z Z', which are made to conform to the fire-plates D, but are a little way apart from them, thus forming the water-passages B, which latter are closed below, but 90 communicate with, the interior of the vessel A at the openings L L', and they also communicate with said passages P P' around the corners of the confine D². Said water-passages, with the plates D D', the sections Z Z', 95 and the side pieces, V V', all unitedly attached to said bottom, as shown and described, form a jacket, in which water while being heated is in perpetual circulation, the hotter portion rising in the passages B and passing 100

- into the vessel A at the openings L L', and a colder portion replaces the transferred hotter portion by flowing from said vessel A through the openings r into the passages P P'. Said 5 jacket—for brevity's sake denoted by the letter Q—is provided with the discharge-tube N, having the pivoted gate M. The same is so located and adapted that the water in both the vessel A and in the jacket Q may be thoroughly 10 discharged to clear them of sediment. The openings L, L', and r are provided with wire-gauze or other suitable strainers, to prevent small fabrics or pieces of clothing being floated into said jacket.
- 15 The oil-stove J, provided with the burners H and base K, is shown mounted upon a platform, R, and the latter placed upon the cross-pieces a', attached to the supports a at such elevation that the top of the stove is kept 20 projected within the fire-box D².

I claim—

1. The combination of the vessel A, having the hipped bottom E E', and the pendent water-jacket Q, opening at different levels into vessel A, and comprising the side plates, V 25 V', the fire-plates D D', forming the flues, and the skirting-sections Z Z', substantially as and for the purposes set forth.

2. The combination of supporting-frame a' 30 vessel A, having hipped bottom E E', depending water-jacket Q, opening into the vessel A at different levels and forming the confine and flues, support R, and the heater projecting into the confine, substantially as and for the purposes herein shown and described. 35

JOHN W. ANDERSON.
